His ATTORNEY.

UNITED STATES PATENT OFFICE.

JOHN F. BELL, OF PLEASANT HILL, MISSOURI.

ANCHOR.

Application filed June 10, 1925. Serial No. 36,187.

My invention relates to improvements in anchors. It is particularly well adapted for use as an anchor designed to be used by an operator of an automobile to pull the machine from a mired condition.

One of the objects of my invention is to provide a novel anchor of the kind described, which is light, strong, cheap, can be folded to compact form for storage or transportation, which will enable a person alone to pull a machine from the mire, and which is efficient in operation.

The novel features of my invention are hereinafter fully described and claimed.

In the accompanying drawing, which illustrates the preferred embodiment of my invention:—

Fig. 1 is a plan view of my improved anchor shown attached by a block and tackle mechanism to an automobile axle.

Fig. 2 is a side elevation, partly broken away, of the same.

Fig. 3 is a top view of the anchor shown in the completely folded condition, with the brace removed.

Fig. 4 is a side elevation, partly broken away, of what is shown in Fig. 3.

Similar reference characters designate similar parts in the different views.

My improved anchor comprises a base consisting of two horizontal members, preferable channel bars 1, having longitudinal outwardly extending flanges 2 and 3 disposed one above the other. A draft member 4, which is preferably a hook, is attached by two hinges 5 to the members 1 respectively, so that the latter may be swung from the folded parallel position, shown in Fig. 3 to the forwardly converging position shown in Fig. 1, the latter position being the operative one.

Two sets of anchoring teeth 6 are arranged in two rows and respectively pivoted loosely to the webs of the channel bars 1 by transverse bolts 7. The teeth of each row respectively extend through vertical slots 8 in the adjacent flange 2 and through vertical slots 9 in the adjacent flange 3. The teeth are arranged to be swung to the operative position, shown in Fig. 2, in which they will extend above and below the bars 1, and below the bars 1 will incline forwardly and downwardly, so as to be drawn into the ground, when a forward pulling strain is placed upon the hook 4. In the operative position, each tooth will bear at its front

edge against a shoulder 10 at the front end of the adjacent slot 8, and at its rear edge it will bear against a shoulder 11 at the rear end of the slot 9, thus eliminating strain 60 upon the bolts 7, which are intermediate of the shoulders 10 and 11.

Two bars 12 are respectively pivoted by bolts 13 to the two sets of teeth 6 above the bars 1. By means of these bars 12 the teeth 6 may be swung to and from the operative position.

The lower portions of the teeth 6 may be disposed wholly above the lower sides of the bars 1 by swinging the bars 12 rearwardly to the position shown in Fig. 4, in which position the teeth 6 will have their lower portions swung upwardly so that the points of the teeth will be above the lower sides of the bars 1 in the slots 9.

A horizontal transverse brace, which may comprise a board 14, is adapted to be placed upon the bars 1 between the latter and the bars 12, as shown in Figs. 1 and 2, when the members 1 are swung to the converging 80 operative position. The bars 1 and board 14 are provided with vertical holes to respectively receive locking pins 15, by means of which the board 14 holds the channel members 1 in the converging operative position. 85

In the operation of the anchor, it is placed upon the ground with the parts disposed in the operative position, shown in Figs. 1 and 2, and a suitable block and tackle mechanism is connected to the draft hook 4 and to the 90 adjacent axle 16 of the machine which is to be pulled from the mire. Such block and tackle mechanism may comprise the following described parts:—A pulley block 17 having a pulley wheel 18 and a ring 19 mounted thereon, is connected to the draft hook 4 by the ring 19. A similar pulley block 20 having mounted thereon a pulley wheel 21 and a hook 22, is attached by the hook 22 to the axle 16. A rope 23 attached to the block 100 20 passes to and around the pulley wheel 18, thence to and around the pulley wheel 21, and thence over the board 14. The operator then sits on the board 14, which serves as a seat, and pulls on the rope 23. His weight 105 and the pull on the rope 23 serves to force the teeth 6 into the ground, after which, by continual pulling of the rope, the operator will be able to pull the machine toward the anchor and out of the mire.

The disposition of the teeth 6 in converging rows in the ground enables them to

withstand a very strong pull without liability of the anchor being pulled ahead from the anchoring position, the teeth being spaced apart and all being in different longitudinal vertical planes. The loose pivoting of the teeth on the bolts 7 permits the teeth to bear wholly against the shoulders 10 and 11 of the members 1, thus removing strain from the bolts 7.

10 After the machine has been withdrawn from the mire, the hook 22 and the ring 19 are respectively detached from the axle 16 and draft hook 4. The pins 15 are withdrawn from the board 14 and bars 1 and 15 the board 14 is removed. The bars 1 are then swung to the parallel position, Figs. 3 and 4, and the bars 12 are swung to the rear position, Fig. 4, in which the teeth 6 will have their lower portions stored wholly 20 within the bars 1.

The anchor will now be in compact condition for storing and transportation.

I do not limit my invention to the structure shown and described, as many modifications, within the scope of the appended 25 claims, may be made without departing from the spirit of my invention.

What I claim is:—

1. An anchor comprising a base consisting of two horizontal members hinged to each other at their front ends and arranged to be swung from a position parallel with each other to a position in which the members will converge forwardly, a removable 35 brace having means for being attached to said members for holding them in the converging position, and anchoring teeth attached to said members and adapted to enter the ground and extending downwardly and forwardly below said members.

2. An anchor comprising a base consisting of two horizontal members hinged at their front ends to each other so as to be 45 swung from a parallel position to a forwardly converging position, a brace removably attached to said members for holding them in the converging position, and anchoring teeth pivoted to each of said members and arranged to be swung to and

from a position in which they will project 50 below said members and will incline downwardly and forwardly.

3. An anchor comprising a base consisting of two horizontal members hinged together at their front ends so as to swing to and 55 from a forwardly converging position, a brace removably attached to said members for holding them in the converging position, anchoring teeth arranged in two rows respectively pivoted to said members so as 60 to swing to and from a position in which they will project below said members and incline forwardly and downwardly, and two bars pivoted respectively to said two rows of teeth.

4. An anchor comprising a draft member, two horizontal members pivoted at one set of ends thereto so as to swing to and from a forwardly converging position, two rows 70 of teeth respectively pivoted to said horizontal members and adapted to swing thereon to and from a position in which they will incline forwardly and downwardly below said two members, a brace removably attached to said two horizontal members for 75 holding the latter in the converging position, and two bars pivoted respectively to said two rows of teeth.

5. An anchor comprising a base consisting of two horizontal members hinged at their 80 front ends to each other so as to be swung from a parallel position to a forwardly converging position, bracing means connecting said members for holding them releasably in the converging position, and anchoring 85 teeth attached to and extending below said members.

6. An anchor comprising a base having draft attaching means and two shoulders, and an anchoring tooth pivoted to said base 90 intermediate of said shoulders and adapted to be swung to and from an anchoring position extending below said base in which position it will have a bearing against both of said shoulders.

In testimony whereof I have signed my name to this specification.

JOHN F. BELL.
